E. R. Morrison

UNITED STATES PATENT OFFICE.

E. R. MORRISON, OF BROOKLYN, NEW YORK, ASSIGNOR TO S. C. HILLS, OF SAME PLACE.

SHINGLE-MACHINE.

Specification of Letters Patent No. 26,463, dated December 13, 1859.

To all whom it may concern:

Be it known that I, E. R. MORRISON, of Brooklyn, in the county of Kings and State of New York, have invented a new and Improved Shingle-Machine; and I do hereby declare that the following is a full, clear, and exact description of the same, reference being had to the annexed drawings, making a part of this specification, in which—

10 Figures 1 and 2, are side sectional views of my invention taken in the line x, x , Figs. 3 and 4. Fig. 3, is a transverse section of ditto, taken in the line y, y , Fig. 1. Fig. 4, is a plan or top view of ditto.

15 Similar letters of reference indicate corresponding parts in the several figures.

This invention relates to an improvement in that class of shingle machines in which the shingle is rived from the bolt with parallel sides and then planed or shaved in proper taper form.

20 The object of the within described invention is to obtain a simple machine for the intended purpose and one that may be very readily manipulated by a person of ordinary tact or ability.

To enable those skilled in the art to fully understand and construct my invention I will proceed to describe it.

25 30 A, A, represents two parallel bars which are connected by suitable cross bars a , and which are increased in depth at one end to be of suitable dimensions to receive sides B, B, the ends of which are fitted and work in grooves b, b , in the inner surfaces of the bars A, at right angles with each other, see Figs. 1 and 2.

To the inner end of each slide B, B, a planer or knife C, is attached, the knives 35 extending the whole width of the slides and secured thereto by screws or bolts. In the outer part of each slide B, and at their inner sides, plates D, are connected by teeth c , which fit in corresponding recesses in the slides and form what may be termed a gear attachment which will be fully understood by referring to Figs. 1 and 2. The plates D, are provided with journals d , at their inner ends, said journals having their bearings in 40 the bars A, A, and the journals of one plate being directly over and in the same plane with those of the other. The journals d , at one end extend through their bar A, and are connected by a toothed or geared portion e , 45 as shown clearly by the dotted lines in Figs. 1 and 2.

To the uppermost geared journal d , a bar E, is attached, said bar being parallel with the bars A, A, and having its outer end provided with a forked pin f , which is fitted 60 on a cleat or ledge F, formed of an inclined and horizontal portion g, h , as shown by dotted lines in Figs. 1 and 2, and attached to one side of a bed G, which is fitted on dove-tail guides or ways i, i , on the bars 65 A, A.

On the cross bars a , of the longitudinal bars A, A, slats j are attached, said slats being parallel with the bars A, A, as shown clearly in Fig. 4. 70

The bed G, is formed of two parallel bars k, k , connected at their outer end by a traverse bar l , and having a board or plate m , fitted between which board or plate is attached to the bar l , only of the bed, so as 75 to allow the inner end of the board or plate to yield or give to a certain extent. To the under side of the inner part of the plate or board m , pendants n , are attached, the lower parts of which at their inner sides 80 are inclined, as shown clearly in Figs. 1 and 2. The pendants n , extend down directly over and between the spaces between the slats j . On the inner part of the upper surface of the board or plate m , a riving 85 knife H, is secured. This knife is simply a steel plate having a cutting edge formed by a basil at its under side, as shown in Figs. 1 and 2. The plate or board m , at its inner part and at its upper surface is re- 90 cessed longitudinally for a short distance as shown at o .

Directly over the bed G, a transverse bearing-piece I, is placed. This bearing-piece may be formed of two transverse bars 95 p, p , attached to uprights r, r , secured to the bars A, A. The bar p , is provided with journals at its end, and they are allowed to rock in their bearings. To the bar p , a plate s , is attached, which plate extends the 100 whole width of the plate m , and has projections t , at its under side which register with the recesses o , in plate m .

The inner end of the knife H, projects a trifle beyond the inner end of the bed G, 105 and to one of the uprights r , a spring or yielding bar u , is attached, having a horizontal projection v , at its inner end which extends over the end of the bed G.

I', represents a plate, the ends of which 110 are attached to bars a', a' , that are secured one to each bar A. To one of the bars a' ,

a spring b' , is attached, said springs having a tendency to keep the plate I , down toward the slats j .

The operation is as follows: The device 5 is attached in an inclined position to any suitable framing, see Fig. 3, and a reciprocating movement is given the bed G , in any proper way. The operator stands by the side of the machine and the bolt, shown 10 in red, is previously got out of proper dimensions and is placed on the bed G , between the bearing-piece I , and the knife H . As the bed G , moves outward in the direction of arrow 1, the knife H , rives a 15 shingle from the lower part of the bolt, the bearing-piece I , retains the bolt while it is acted upon by the knife. The knife H , passes over the plate I , and the latter consequently insures a complete cut of the 20 knife and a proper discharge of the shingle on the slats j , the bolt being retained when the bed has reached the termination of its outward stroke by the outer part of the knife H , and the projection v , see Fig. 2. 25 On the return movement of the bed G , as indicated by the arrow 2, the shingle on the slats j , is shoved by the pendants n , under the plate I' , and between the planers or 30 knives C , C , which as the shingle enters the space between them are distended the full length of their movement by the plates D , D , and bar E , which are actuated by the ledge or projection F , at the side of the bed G . The knives C , C , are kept distended a 35 certain length of time, as the bed moves in the direction of arrow 2, in consequence of the horizontal portion h , of the ledge or projection F , and by this means the shingles are shaved or planed with parallel upper and lower surfaces for a short distance 40 near the butt, and are then planed in taper form in consequence of the inclined portion

g , of the ledge actuating the bar F . The inclined surfaces of the pendants n , have a tendency to keep the shingle down on the 45 slats j , as the bed G , moves in the direction of arrow 2, and the plate I' , also presses on the shingle. As the bed G , approaches the termination of its inner stroke or movement indicated by arrow 2, the plate I' , is raised 50 and the finished shingle drops by its own gravity aided by the inclination of the machine. The bed G , as it passes underneath the bolt throws out the projection v , and the bolt passes or falls on the plate m , ready 55 for a succeeding cut as the bed moves outward in the direction of arrow 1. The yielding bottom plate or board m , compensates for any winding or irregularity of the grain of the bolt and thereby prevents any 60 binding tendency during the operation of the knife H . The projection v , as the bed G , moves outward is forced inward by the elasticity of the bar u , so as to be in proper 65 position to sustain the bolt when the succeeding shingle is cut from it.

Having thus described my invention what I claim as new and desire to secure by Letters Patent, is—

1. The arrangement of the knife H , and 70 projection v , in connection with the reciprocating bed substantially as shown whereby the bolt is supported as the bed passes underneath it during the cutting or riving operation.

2. The employment or use of the planers or knives C , C , operated by the plates D , D , bar E , and ledge or projection F , on the bed G , substantially as and for the purpose described.

E. R. MORRISON.
